UNITED STATES PATENT OFFICE

ANTHONY ALESSI, OF PATERSON, NEW JERSEY, ASSIGNOR TO SELECTO LIGHT, INC., OF PATERSON, NEW JERSEY, A CORPORATION OF NEW JERSEY

DESIGN FOR A VEHICLE LAMP

Application filed October 21, 1932. Serial No. 45,434. Term of patent 14 years.

To all whom it may concern:

Be it known that I, ANTHONY ALESSI, a citizen of the United States, residing at Paterson, in the county of Passaic and State of New Jersey, have invented a new, original, and ornamental Design for a Vehicle Lamp, of which the following is a specification, reference being had to the accompanying drawing, forming part thereof.

Fig. 1 is a front elevation of a vehicle

lamp showing my new design and Fig. 2 is a side elevation of the same.

The faceted conical portions of the lamp are glass or the like for permitting light within the lamp to escape therefrom.

I claim:

The ornamental design for a vehicle lamp, as shown and described.

In testimony whereof I affix my signature.

ANTHONY ALESSI.
